TOOTHBRUSH HOLDER

Filed Jan. 9, 1929

FIG. 1.

FIG. 2.

INVENTOR:
Albert M. Bernier
BY David E. Carlson
ATTORNEY

UNITED STATES PATENT OFFICE

ALBERT MARCELL BERNIER, OF ST. PAUL, MINNESOTA

TOOTHBRUSH HOLDER

Application filed January 9, 1929. Serial No. 331,330.

My invention relates to brush holders in general and more particularly to a tooth brush holding device.

The main object is to provide a simple, inexpensive and efficient device for holding tooth brushes and said device embodying certain features of construction and uses hereinafter fully set forth reference being had to the accompanying drawing, in 10 which,—

Fig. 1 is a slightly perspective front view of the main channel member of my device in upright position.

Fig. 2 is also a slightly perspective front 15 view but showing the complete device with a tooth brush retained in it.

Fig. 3 is a perspective view of a secondary shell or channel member comprising that 20 part of my device which retains the head or bristle part of a tooth brush.

Fig. 4 is a modification of Fig. 3.

Referring to the drawing by reference letters, A designates an elongated, normally upright channel member of shallow U-shape in cross section or resembling a standard channel iron. At the upper end of said channel, in its web, is provided an aperture A2 for suspending this main channel by means of a nail or screw (not shown) on 30 a wall with the flange edges against the wall and the web of the channel being of course spaced parallel thereto.

Near the upper end of the channel is provided a group of apertures D in the web at the two edges of said web adjacent said apertures are a number of inwardly directed struck-up tongues G, under which are frictionally but removably retained the parallel side flanges F of a brush-retaining housing 40 E also of channel like formation but open downwardly and closed at its upper end (see Fig. 4).

The entire device so far described may be of any suitable sheet material and housing 45 E may preferably be of transparent material as indicated in Fig. 2. It will be readily understood that housing E may be permanently retained on the main member by closing the tongues G down upon its flanges F or the said housing E may be only

frictionally held thereby but removable if desired when the device is to be washed or sterilized.

Near the lower end of the main channel is fixed a metal strip or band I arched outwardly and centrally from the web to provide an opening H for retaining the end part of a tooth-brush handle opposite its bristle end, the tooth brush being designated K and its bristles K2 (Fig. 2).

In the use of the device a tooth brush is inserted upwardly under the smaller housing E with its bristles against the web of the main member on its perforated part, the head of the brush being frictionally retained between the web of member E and the web of the main member and the lower end of the brush handle is simply slipped downwardly within the band I. After being used a tooth brush contains some moisture or 50 may be quite saturated and being placed as described it easily drains and is rapidly dried by air circulating freely through the apertures or perforations D and into the bristles.

The top of member E being closed it is obvious that the brush is protected from dust settling in the room. Obviously a brush retained in my device as above described is easily removed for use. Furthermore with 55 the upper end of casing E closed air circulating upwardly through its open end passes outwardly through the bristles and the apertures D to rapidly dry the brush and prevents deterioration of the bristles.

I claim:

1. A brush holder of the class described comprising an elongated normally upright main channel member and means provided for retaining same in vertical position with its web in spaced relation to a wall, the upper part of said web provided with a group of apertures, an upright casing on the upper part of said web with a wall in spaced relation to said apertured part of the channel web, said casing having a downward opening, to receive the bristle part of a brush inserted upwardly, tooth-brush handle engaging means on said main member

in spaced relation below said apertured web part.

2. The structure specified in claim 1 in which said casing comprises an elongated shell of U-shape in cross section and outward side flanges thereon and means on said main channel adapted to removably retain said flange parts, the said casing formed with an upper closed end.

10 3. The structure specified in claim 1 in which said means for retaining the lower end of tooth brush comprises an outwardly directed band of half-loop form extending integrally and outwardly from the lower end 15 part of the main member.

4. The structure specified in claim 1 in which said casing comprises an elongated shell of U-shape in cross section and outward side flanges thereon and means on said main channel adapted to removably retain said flange parts, the said casing formed with an upper closed end, said flange engaging means on the main channel comprising at each of the opposite edge parts of 25 the web a number of struck-up tongues directed inwardly in parallel relation to said web to slidably receive the said outer flanges of the casing.

ALBERT MARCELL BERNIER.
